(57) **CLAIM**

An ornamental design for a steamer body, as shown and described.

DESCRIPTION

FIG. 1 is a front top left perspective view of a steamer body showing our new design therefor, the bottom plate and handle being shown in phantom line and forming no part of the design;

FIG. 2 is a top plan view thereof;

FIG. 3 is a side elevational view thereof, the presser plate being shown in phantom line and forming no part of the design;

FIG. 4 is a front elevational view thereof; and,

FIG. 5 is a rear elevational view thereof.
